ANNEALING FURNACE

Alfred J. Castle, Chicago, Ill., assignor to Inland
Steel Company, a corporation of Delaware

Application August 25, 1944, Serial No. 551,207

2 Claims. (Cl. 263—28)

1

This invention relates to an annealing furnace. In the operation of open fired annealing furnaces for the handling of iron and steel products, such particularly as cold and tin mill products, it was heretofore necessary to fire the furnaces slowly in order to procure uniform temperatures from top to bottom of the material being annealed (which material will sometimes be referred to herein as the "work"). If such furnaces were heated more rapidly than was the practice, the top temperatures became very much higher than the bottom and produced unsatisfactory annealing.

While the former annealing furnaces differed considerably in their structure, they were all characterized by the presence of a platform upon which the products to be annealed were disposed, and these products were placed in stacks which reached from the platform well toward the roof of the furnace. Furthermore the products were covered by metal hoods or covers which were sealed against air at their edges by the use of sand or other material.

The furnaces were proportioned so that the walls were as close as practicable to the covers and these walls were lined with refractory material which, during operation of the furnace, radiated and reflected radiant heat. The proportions of the furnaces, however, differed somewhat, depending on the shape and character of the products to be annealed therein.

The furnaces have been fired in different manners. In one type the flame was directed vertically near a side wall of the furnace. In another type of furnace the flame was directed horizontally beneath the platform. This method does not permit faster firing, however. When horizontally firing, a reducing or incompletely consumed gas was necessarily used to avoid overheating the platform itself. It was the general practice, due to inadequacy of the furnaces, to use heavy covers over the annealing material to avoid local overheating if the furnace was to be fired at its maximum rate. These heavy covers delayed heat transfer and slowed down the annealing process.

Furnaces were also heated by internally fired tubes, this type being known as the radiant tube annealing furnace. In the radiant tube furnaces firing was slow because the top temperature within the tube was limited, by the characteristics of the metal of the tube, to 1600° to about 1800° F.

It was characteristic of the past processes that the top temperature of the material would tend to become unduly high before the bottom had reached the minimum annealing temperature. Therefore, firing was slowed after the peak per-

2

missible temperature had been reached in the top material, and the work held in the furnace to obtain temperature equilibrium throughout. This, of course, slowed down the output of the furnace.

In the present apparatus and method the structure of the furnace is basically the same as in previous open fired furnaces but means are provided in the side walls for breaking up convection currents and directing a greater proportion of the heat to the lower portion of the products being annealed. By correlating the position of the flame with respect to the wall and a heat deflecting baffle, and the relative size and position of the platform cover and furnace walls, it has been found possible under plant operating conditions to maintain a temperature difference between the top and bottom of the material undergoing annealing to as little as 50-60° and with the lowest temperature at or above the minimum annealing temperature, and to maintain this relationship during the annealing operation while firing at a rate such that the time required for annealing is substantially reduced. Firing at an increased rate permits improved combustion with a higher combustion temperature. The higher firing rate also increases the velocity of the combustion gases. Heat transfer from these gases is improved with the increase in velocity. This is particularly true at the bottom of the furnace where increased heat transfer is especially desirable. It has likewise been possible to eliminate the heavy covers in cases where formerly they were required in the cold mill furnaces, and to substitute therefor covers only about $\frac{1}{4}$ inch in thickness.

As a result of all of these factors, the output of the cold mill furnaces has been multiplied as much as four to six times. For example, in a furnace where the former output was approximately $\frac{1}{2}$ ton per hour, the introduction of the present changes produced an output of as much as 2 to 3 tons per hour.

In the tin mill furnaces firing was usually perpendicular and light covers were normally employed. In these furnaces, however, the output has been also greatly increased by the present invention, for example, from 1.4 tons per hour to 3 tons per hour, using the same sized coils in each case.

In its preferred form, the present invention comprises a vertically directed flame which impinges upon an inclined baffle of refractory material having a heat deflecting surface directing a substantial portion of the heat from the side wall to the cover. The particular angle depends upon the proportions of the furnace and the position and volume of the material being annealed.

The baffles establish a substantial radiating

surface at a temperature very much higher than that of the adjacent walls. This area is adjacent the lower portion of the material being annealed, and at the same time directs its radiant energy, as well as the combustion gases, toward that lower portion of the material. As already pointed out, it permits more rapid firing which produces a higher flame temperature. The proximity of the baffles to the flame, and the high temperature of the baffles, by reducing radiation from the flame, likewise tend to increase its temperature. The higher temperature, the increased firing, and the reduction in available space, all increase the velocity of the combustion gases, and the baffles direct these toward the portion of the work where they are most needed.

The invention is illustrated in the drawings in which Figure 1 is a view taken along line 1—1 of Fig. 2 and showing an end elevation in section of a typical cold strip mill annealing furnace; Figure 2 is a longitudinal sectional elevation through the furnace; Figure 3 is a sectional end elevation of a typical tin mill furnace; Figure 4 is a longitudinal sectional elevation taken along the line 4—4 in Figure 3; and Figure 5 is an end elevation in section of a modified form of baffle for a cold strip mill.

The figures are drawn to scale, the distance from the center of the platform in Figure 1 to the inside of the side wall of the furnace being 5 ft. 6 inches at the farthest point. The over-all length of the furnace from inside wall to inside wall is 18 ft. 5 inches, as shown in Figure 2. The furnace shown in Figure 3 has an interior at the widest point of 14 ft. 1½ inches, and, as shown in Figure 4, has an over-all inside length of 26 ft. 1½ inches, representing the longest dimension on the inside of the roof.

The furnace 10 shown in Figure 1 comprises refractory side walls 11 and a refractory roof 13. A series of burners 15 is arranged at the base of the wall 11 and are spaced 9 inches apart from center to center. A baffle 16 runs from one end of the wall 11 to the other and has a face 17 inclined inwardly in an upward direction at a sharp angle from the vertical. The face of the baffle is approximately 19½ inches in a straight line and is then slightly curved as indicated. The upper portion of the baffle is inclined downwardly in an inward direction to form the face 18. As shown, the angle is approximately 28° from the vertical. The upper face 18 is sloped at about 20° from the horizontal. The burners are separated by the transverse walls 20 into groups of three.

The material to be annealed which will here be designated as the work 25, is mounted upon a platform 26 and covered by a metal cover 27. As already explained, this cover may be very thin, for example, $\frac{1}{8}$ inch plate. The platform itself comprises the central work carrying area 28 which is surrounded by a trough 29 bounded on the outside by the flange 30. The lower edges 31 of the cover extend into the trough 29 and are sealed by sand 32. The platform is carried on a frame which in turn is mounted on any suitable carriage such as the wheels 33 operating on the truck 34. Products of combustion are removed from the furnace through a chimney 12.

In operation of the structure the work is mounted on the platform 26 covered by the cover 27 and sealed with sand 32. It is then run into the furnace and the door closed. The burners, which customarily burn hydrocarbon vapor or liquid, are lighted and fired with a hot or oxi-

dizing flame. The length of the flame is such that little, if any, of it extends beyond the end of the baffle, but the convection currents which would otherwise tend to flow upwardly along the walls 11 are broken up and some of the convection heat diverted to the covers and the material thereunder. More important, however, as the baffles become hot, the radiant heat therefrom is deflected and concentrated on the lower portions 10 of the covers directly above the platform. Whatever may be the theoretical operation of the baffle, however, in actual practice it has produced remarkable uniformity of product and greatly reduced the temperature difference between the 15 top and bottom of the work. This is illustrated by the following typical runs in furnaces constructed as shown in Figures 1 and 2:

181,840 lbs. of strip were charged in the furnace and temperature recordings were taken at 20 the following points:

- (a) 6 inches above the bottom at the front.
- (b) 6 inches above the bottom at the back.
- (c) Top back.
- (d) Top front.
- (e) 18 inches above the bottom at the back.
- (f) 18 inches above the bottom at the front.
- (g) Furnace temperature taken at the usual roof position.

A thin cover was used in this operation and the output was 2.84 tons per hour.

In another and shorter operation 162,140 lbs. of strip was charged to the furnace. Temperature readings were made at the following points:

- (a) Left front 6 inches above the bottom.
- (b) Right center 6 inches above the bottom.
- (c) Right front 18 inches above the bottom.
- (d) Center 18 inches above the bottom.
- (e) Top back.
- (f) Top front.
- (g) Furnace temperature.

75 The output was 2.89 tons per hour.

In the structures shown in Figures 3 and 4 the proportions of the furnace and the proportions of the baffle are somewhat different. There, the furnace 10a is provided with side walls 11a, the ceiling 13a, burners 15a and baffles 16a. In this case the angle of the lower face 17a of the baffle is approximately 45° and the lower edge of this face is slightly above the edge of the platform 26a. Furthermore the upper face 18a is level, and a vertical partial forward face 40 is provided between the inclined face 17a and the upper face 18a. A rather elongated vertical face 41 is provided immediately adjacent and above the burner. The combustion gases pass upwardly to the roof of the furnace, downwardly between the covers 27a, and out through the flue 42 at the base of the structure. Because of this path of the gases it is possible to locate the baffle at a somewhat higher position with respect to the platform than is the case in the cold mill furnaces.

As will be readily understood, the exact proportions and location of the baffle will depend upon the burner, the way it is operated, the size and shape of the furnace, and the character of the work to be annealed. In all cases these are correlated to produce a substantially uniform temperature from top to bottom of the work.

The following are typical runs with and without baffle in a tin mill annealing process, in furnaces constructed as shown in Figures 3 and 4. In these operations the platform carried ten covers which were numbered from the door toward the rear of the furnace. The covers were mounted in pairs, the left-hand cover in the first pair toward the door being numbered 1, and the second member of that pair, 2. This numbering system was repeated until the last pair at the rear of the furnace was numbered 9 at the left, and 10 at the right. The thermocouple readings are indicated in each table. Furnace temperature is taken in the customary location at the top of the furnace. The other column headings indicate by the number the particular cover concerned and the initial B indicates that the thermocouple was at the bottom of the cover, and the initial T indicates that the temperature was taken at the top of the cover.

Without baffle normal operation

140,690 lbs. of metal were charged. The operation required 40 hours and the output was 1.7 tons per hour.

22		1,200	1,130	1,130	1,160	1,170

Part of the saving in time produced by the new furnace is due to increased efficiency of heat distribution. Some of the improvement in time is due to the fact that the furnaces may be fired at a faster rate. In the tin mill accurate gas consumption figures are maintained and with the old type furnaces without the baffle, the average consumption is 2679 cubic feet of gas per ton of metal annealed. With the baffles, the average consumption is approximately 2370 cubic feet per ton. On the basis of an average time of 40 hours for the former process, the firing rate was approximately 67 cubic feet per hour per ton, whereas with the new process on the basis of an average of 24 hours' treatment, the firing rate would be 100 cubic feet of gas per ton per hour. It is thus apparent that the firing rate is approximately 50% greater than before but the total consumption is approximately 11.5% less.

In the modified form shown in Figure 5, the furnace 10b is provided with refractory side walls 11b and a refractory roof 13b. The series of burners 15b is arranged at the base of the wall 11 and spaced 9 inches apart from center to center. The baffle 16b runs from one end of the wall 11 to the other and has a face 17b inclined inwardly in an upward direction at a sharp angle from the vertical. The face of the baffle is approximately 15 inches in a straight line. The upper portion of the baffle is horizontal and forms the face 18b approximately 9 inches in width. The vertical projection of the face 17b is approximately one foot. The corner 50 between the face 17b and the face 18b is cut off to form the vertical face about one inch in height. The entire baffle is horizontally offset from the wall 11b approximately 4 inches, and this is accomplished at the upper side by the vertical face 51 approximately 4½ inches in height, and the horizontal face 52 approximately 4 inches in width. The platform 26b, upon which the work 25b is mounted, has its upper edge 54 approximately 2 inches above and 4 inches inside the corner 50 of the baffle.

It will be observed that the exact size, angle, and disposition of the baffle varies in the different furnaces shown. In all cases the size, shape and position of the baffle is correlated to the size, shape and position of the platform and of the work thereon to produce substantially uniform annealing temperatures under full firing operation. It will also be observed that the baffles, platforms, and the work, may be considered to bound or define the combustion zone of limited area. The gases impinge upon the baffles before they are completely consumed. They are then deflected toward the platform and the work. The platforms and the work thereon thus enter into the

8
structure of the furnace in order to obtain maximum efficiency.

One of the improved results in the operation of the new furnaces is that strip in coil form may be coiled considerably tighter than was heretofore the case. This not only permits a greater volume of material to be treated at one time but the tighter winding of the coils establishes better heat transfer. It is also advantageous in the later handling of the strip. It has been discovered that previously the maximum tension usable was 700-1050 lbs. per square inch per inch of width, depending upon the type of treatment and the type of material employed. This has now been increased to 1400-1750 lbs. per square inch per inch of width.

The term "sheet metal" is used herein to cover thin metal whether technically in strip or sheets.

The foregoing detailed description has been given for clearness of understanding only, and no unnecessary limitations should be understood therefrom.

What I claim as new, and desire to secure by Letters Patent, is:

25 1. In an annealing furnace for sheet metal products having side walls and a closed roof of refractory material, a platform within the furnace for the disposition of the material to be annealed, burner means arranged adjacent the sides of the platform, and a downwardly facing refractory baffle above but adjacent the platform and projecting inwardly from a side wall, said baffle having an upwardly and inwardly inclined side surface and an upwardly and outwardly inclined top surface, said side wall being above the baffle and said burner means being located at the base of said baffle and being substantially the sole heating means for the furnace.

2. An annealing furnace for sheet metal products having side walls and a closed roof of refractory material, a movable car adapted to be arranged within said furnace below the bottoms of said side walls, a platform on said car for the disposition of the material to be annealed, burner means arranged adjacent and below said platform, and a downwardly facing refractory baffle adjacent the platform and above the burner means and projecting inwardly from a side wall, said refractory baffle being located below said side wall with the burner means located at the base of said refractory baffle and being substantially the sole heating means for the furnace, the baffle having an upwardly and inwardly inclined side surface and an upwardly and outwardly inclined top surface.

ALFRED J. CASTLE.
